UNITED STATES PATENT OFFICE.

PHILIP A. LUCKETT OF PHILADELPHIA, PENNSYLVANIA.

UNDERGARMENT.

1,339,116.

Specification of Letters Patent.

Patented May 4, 1920.

Application filed July 29, 1919. Serial No. 314,033.

To all whom it may concern:

Be it known that I, PHILIP A. LUCKETT, a citizen of the United States, residing at Philadelphia, in the county of Philadelphia and State of Pennsylvania, have invented new and useful Improvements in Undergarments, of which the following is a specification.

My invention relates to under garments and particularly to drop seat structure therein.

The object of my invention is to provide an under-garment having a drop seat opening at both sides below the waist line and secured by only a single fastening means. I also provide a drop seat having a single fastening means located near the center of the back, allowing the seat flap to drop symmetrically. A further object is to provide a drop seat having a single fastening, and one which has no tendency to gap, though it provides a transverse opening across substantially the entire width of the garment.

Numerous attempts have been made to provide a practical drop seat structure having only one detachable fastening, the convenience of which is obvious. Such structures, however, have uniformly been made unsymmetrical, opening from one side only and requiring considerable stretching and distortion of the garment to provide an adequate opening. Such garments furthermore have a tendency to gap and sag due to the fact that they have a transverse upper edge supported at its opposite ends only. In my improved garment I combine the convenience of a single detachable connection with the full opening advantages of the usual straight top drop seat, opening down both sides, and further arrange the parts of the garment so that the tendency to gap is eliminated. Other objects and advantages will be apparent from the following description taken in connection with the accompanying drawings in which;

Figure 1, is a rear view of the garment showing the flap in closed position;

Fig. 2, is a similar view showing the flap open.

My invention includes a union garment having the usual front portion 10 which preferably is open from the neck to a point near the crotch with the usual detachable connections for the edges thereof. It also has the usual rear body portion 11. The

seat portion is formed by an upward continuation of the rear leg portions 12 and is tapered from points 13 in the side seams to form a triangular seat flap 14 having a button hole at its upper pointed end 15 adapted to engage a button 16 at approximately the waist line of the wearer. The upper edges of said flap 14 are preferably slightly concave from points 13 to end 15 to decrease any tendency to gap at this point and to insure a snug fit along the curve of the wearer's body.

While the seat flap has been described as extending to the side seams of the garment it will be apparent that the garment may be constructed without side seams, the front portions of the garment being cut to extend around the sides and rear of the legs to form the seat flap. Regardless of the exact method of constructing the seat, the opening will extend substantially across the entire width of the garment. This will permit points 13 to be located relatively high in the legs, an advantage over former structures where the opening along the side seam was at one side of the body only and had to extend nearly to the bottom of the leg.

The rear body portion 11 is extended downwardly below the waist line and has its lower edge underlying and spaced at an approximately uniform distance from the upper edge of the seat flap 14. This arrangement, as will be seen from Fig. 2, produces a sharp upward curve in the middle portion of said lower edge of the rear body portion 11, which underlies flap 14. This upward curve is of decided advantage in accommodating the garment to forward bending motions which make it necessary for the seat of the garment either to expand substantially or to bind the wearer. It will be apparent that if the lower edge of this underlying portion were even approximately straight, it would bind sharply across the wearer's buttocks. If desired this extension of the rear body portion below the waist line may be composed of a separate piece of material 19.

To facilitate bending of the body in a forward direction I may insert an elastic element in the vertical line of the upper end 15 of the seat flap 14. This elastic element may consist of the common transverse elastic strip 17 located at the waist line between rear body portion 11 and its extension 19,

or it may consist of an elastic strip located in the flap 14, preferably adjacent the tip 15 thereof as shown at 18. If desired both these strips may be used as illustrated in Fig. 1.

It will be seen that my garment provides a complete seat closure free from sagging, having a single point of attachment and providing a full symmetrical opening. It 10 is also particularly comfortable to wear, having resilient portions for accommodating direct bending movements and having overlapping portions at the sides which accommodate with special facility movements of 15 the shoulder.

It is obvious also that my invention is applicable to nether garments, and that numerous changes may be made therein without departing from the spirit of my invention as covered in the claims.

What I claim is:

1. A union undergarment having a substantially triangular drop seat supported in closed position by a single detachable fastener located adjacent the center of the back, the edges of said drop seat extending downwardly and outwardly from said fastener to the side seams of the garment to form an opening extending substantially across the entire width of the rear portion of the garment.

2. A union undergarment having a drop seat supported in closed position by a single detachable fastener located adjacent the center of the back, the edges of said seat extending downwardly and outwardly from said fastener to the side seams of the garment to form an opening extending substantially across the entire width of the rear portion of the garment, said edge portions being concave to permit them to conform accurately to the contour of the body regardless of bending movements of the wearer.

45 3. A union undergarment having a drop seat supported in closed position by a single

detachable fastener located adjacent the center of the back, the edges of said seat extending downwardly and outwardly from said fastener to the side seams of the garment to form an opening extending substantially across the entire width of the rear portion of the garment, and a transversely arranged elastic insert located in the vertical line of the detachable fastener and adapted to yield under forward bending movements of the body to reduce the strain on said fastener. 55

4. A union undergarment having a drop seat supported in closed position by a single 60 detachable fastener located adjacent the center of the back, the edges of said seat extending downwardly and outwardly from said fastener to the side seams of the garment to form an opening extending substantially 65 across the entire width of the rear portion of the garment, and a transversely arranged elastic insert located in the drop seat adjacent the detachable fastener and extending from edge to edge thereof and adapted to yield under forward movements 70 of the body to reduce the strain on said fastener.

5. A union undergarment having a drop seat supported in closed position by a single 75 detachable fastener located adjacent the center of the back, the edges of said seat extending downwardly and outwardly from said fastener to the side seams of the garment, and a skirt portion connected to the 80 upper back portion of the garment and extending downwardly beneath the seat, the lower edge of the skirt portion being located below and spaced from the upper edges of the seat throughout the entire width of the 85 garment, said lower edge being curved upwardly adjacent the center line of the garment to prevent constriction of the body during forward bending movements.

In testimony whereof I have hereunto set 90 my hand.

PHILIP A. LUCKETT.
